(Cl. D57—1)

To all whom it may concern:

Be it known that I, Lorenzo del Riccio, a citizen
of the United States, residing at Los Angeles, in
the county of Los Angeles, and State of Califor-
nia, have invented a new, original, and ornamen-
tal Design for a Binocular, of which the following
is a specification, reference being had to the ac-
companying drawing, forming part thereof.

Figure 1 is a side view of a binocular, showing
my new design.

Fig. 2 is a top view thereof.

Fig. 3 is a bottom view thereof.

Fig. 4 is an end view thereof.

I claim:

The ornamental design for a binocular, as
shown.

LORENZO DEL RICCIO.
